UNITED STATES PATENT OFFICE.

THOMAS A. WESTON, OF STAMFORD, CONNECTICUT, ASSIGNOR TO THE YALE & TOWNE MANUFACTURING COMPANY, OF SAME PLACE.

FRICITION-CLUTCH.

SPECIFICATION forming part of Letters Patent No. 396,315, dated January 15, 1889.

Application filed May 11, 1888. Serial No. 273,570. (No model.)

To all whom it may concern:

Be it known that I, THOMAS A. WESTON, a citizen of the United States, and a resident of Stamford, Fairfield county, Connecticut, have 5 invented certain Improvements in Friction-Clutches, of which the following is a specification.

The object of my invention is to construct a disk friction-clutch that can be operated 10 by a minimum of applied pressure, and one wherein the power transmitted shall always be uniformly proportionate to the applied pressure or a constant multiple thereof. When applied to a hoisting-drum, this characteristic enables the operator to determine 15 exactly the hauling effect of the drum by the force he applies to the hand-lever; and when the clutch is applied to a driving pulley or shaft, &c., the coupling or clutch can be operated by a weighted lever, the weight and leverage indicating exactly the transmitted 20 power, beyond which any excess of resistance will simply cause the clutch to slip, thus avoiding breakages and accidents.

25 In the accompanying drawings, Figure 1 is a longitudinal section of my improved clutch as applied to a power-driven hoisting-drum. Fig. 2 is an end elevation, looking in the direction of the arrow, Fig. 1; and Fig. 3 is a 30 sectional perspective view of my improved clutch applied to a driving-pulley for shafting.

I will first describe my invention in connection with the hoisting-drum illustrated in 35 Figs. 1 and 2.

A is the power-shaft of the hoisting-engine, and B' is the friction pulley or clutch, integral with the winding-drum B, A' being a hub securely keyed to the shaft A, and provided 40 on its periphery with keys a', which engage with a series of disks, a, termed the "shaft-disks." To the inner periphery of the rim of the friction-pulley B' are secured keys b', which engage with a series of friction-disks, 45 b, arranged alternately with the shaft-disks a, and which may be termed the "pulley-disks."

B² is a pressure-plate engaging with the keys b' of the pulley, so that said plate is 50 caused to turn with the pulley. This press-

ure-plate is moved toward the disks a b, so as to press them into frictional contact, by means of plain straight levers C, which radiate from a common central collar, D, to their respective pivot-pins c in or near the pulley-rim, the 55 pivot-pins being secured, in the present instance, to bolts E, passing through the rim, and provided with adjusting-nuts e, in order to regulate the position of the pivot-pins c in respect to the face of the pressure-plate B², 60 so as to insure uniform pressure of all the levers and compensate for the effects of wear.

The inner free ends of the levers C are adapted to pockets in the collar D, so that as the collar is moved longitudinally on the 65 shaft the levers C will act uniformly upon the disk B², each lever C being provided with a projection, d, which bears against the disk B²—preferably near its periphery—bearing-plates d' being used, if desired, as shown in 70 Fig. 1.

The collar D is forced inward by any suitable operating hand-lever which is adapted to grooves in the sliding collar F, the thrust of the collar being taken up by the abutment-collar A², which is secured to the shaft A at the opposite end of the hoisting-drum. The outer rim of the friction-pulley B' is formed to receive a brake-strap, G, one end of which is secured to a hanger, H, while the other end 80 is secured to one arm of an operating-lever, I, pivoted at i to the hanger.

It will be seen that as each lever C acts upon the pressure-plate B² at a point near its fulcrum in one of the pivot-pins c, while 85 pressure is applied through the collar D to the extreme inner ends of the levers, a large leverage is gained, thus multiplying the power of the operating-lever and its collar F.

The main feature of the friction-disks a 90 and b is increase of frictional effect, due to the number of pairs of surfaces in the series of disks.

The operation of the friction-drum is as follows: A rope or chain may be fastened to 95 the drum B, wherewith to lift the load, the shaft A being driven by an engine or other motive power, and its rotation being shared by the hub A' and the disks a. The disks b, being secured to the pulley B', are at 100

rest, either from inertia or from the pulley being held by the brake-strap G. When it is desired to hoist a load by means of the drum, the collar F is forced inward sufficiently upon 5 the collar D, thereby pressing the levers C upon the plate B² and frictionally uniting the pulley-disks b with the rotating shaft-disks a, thereby rotating the drum and raising the load. The load may be lowered by relaxing 10 the pressure of the operating-lever upon the collar D, or by applying the brake-strap G with force sufficient to hold the load, and then withdrawing the pressure upon the collar D, so as to free the disks wholly from frictional 15 adhesion, after which the load can be held in suspension or lowered by manipulating the brake-strap G.

In Fig. 3 I have shown my invention applied to a driving-pulley for shafting, &c.; 20 and in place of the series of frictional disks a and b, I have shown the hub A'' extending in the form of a disk between a friction-face, a², on the pulley B and a like friction-face, a², on the pressure-plate B². I preferably face 25 the disk of said hub A'' on one or both sides with a facing of wood or leather for frictional contact with the disk-face of the pressure-plate B² on one side and that of the pulley B' on the other. The hub A'' is so keyed to the 30 shaft that it will turn with said shaft, but will have a slight independent longitudinal movement thereon. The levers C are hung in precisely the same manner as in Figs. 1 and 2; but in this instance I have shown the collar 35 F embraced by a ring, F', having pins adapted to orifices in the forked lever J, secured to a rock-shaft, K, to which is also secured a lever, L, having an adjustable weight, L', at its outer end, by which means the frictional parts of 40 the pulley are brought into and kept in contact. The weight L' and its position upon

the lever may each be varied in order to vary the driving capacity of the pulley and to prevent the transmission of strains beyond the predetermined limit.

45

In referring throughout the specification to a disk friction-clutch, I refer generally to such clutches as require the coupling pressure to take effect in a line or lines parallel with the axis of rotation, so that my invention can be 50 applied to all clutches coming under this class.

I claim as my invention—

1. The combination of a friction-clutch, provided with disk-formed friction-faces, with 55 two or more pressing-levers, each fulcrumed at the pulley-rim, and thence extending toward the pulley-axis, and a sliding collar embracing the free ends of all of said levers, substantially as set forth.

60

2. The combination, in a friction-clutch, of the pulley or drum, the friction-disks, the presser-plate, a series of radiating levers fulcrumed at their outer ends to the pulley or drum, and each having a projection adapted 65 to bear against the presser-plate, and a central sliding collar adapted to act upon the converging ends of the levers, substantially as set forth.

75

3. The combination, in a disk friction-clutch, of the series of radiating levers, the central sliding collar acting upon the converging ends of the said levers, and a pulley or drum carrying adjustable fulcrums for the levers, substantially as set forth.

In testimony whereof I have signed my name to this specification in the presence of two subscribing witnesses.

THOS. A. WESTON.
